Fig. 8.

FIG. 1 is a perspective view taken from the top, front and one side of a shaver holder showing my new design, the opposite side being a mirror image of the side shown;

FIG. 2 is a top view thereof;

FIG. 3 is a rear view thereof; and

FIG. 4 is a bottom view thereof;

FIG. 5 is a perspective view taken from the top, front and one side of a modified form of the shaver holder shown in FIG. 1, the opposite side being a mirror image of the side shown;

FIG. 6 is a top view of FIG. 5;

FIG. 7 is a rear view of FIG. 5; and

FIG. 8 is a bottom view of FIG. 5.

The broken line representation of an electric dry shaver in FIGS. 1 and 5 are for the purposes of illustration only.

I claim:

The ornamental design for a shaver holder, substantially as shown and described.
